UNITED STATES PATENT OFFICE

166,584

GAS STORAGE TANK UNIT

James Patrick Beaird, Shreveport, La., assignor to
The J. B. Beaird Company, Inc., Shreveport, La.

Application July 9, 1951, Serial No. 15,807

Term of patent 14 years

(Cl. D52—2)

To all whom it may concern:

Be it known that I, James Patrick Beaird, a citizen of the United States, residing at Shreveport, Caddo Parish, State of Louisiana, have invented a new, original, and ornamental Design for a Gas Storage Tank Unit, of which the following is a specification, reference being had to the accompanying drawing, forming a part hereof.

Figure 1 is an elevational view of one side of a gas storage tank unit embodying my new design;

Figure 2 is an elevational view of the other side thereof;

Figure 3 is an elevational view of one end, and

Figure 4 is an elevational view of the opposite end thereof.

I claim:

The ornamental design for a gas storage tank unit, as shown.

JAMES PATRICK BEAIRD.
